N. W. KLINE

TENT FRAME

Filed Dec. 31, 1921

UNITED STATES PATENT OFFICE.

NICK W. KLINE, OF LOS ANGELES, CALIFORNIA.

TENT FRAME.

Application filed December 31, 1921. Serial No. 526,145.

To all whom it may concern:

Be it known that I, NICK W. KLINE, a citizen of the United States, residing at Los Angeles, in the county of Los Angeles and 5 State of California, have invented new and useful Improvements in a Tent Frame, of which the following is a specification.

This invention relates to a frame for tents and particularly pertains to a structure for 10 forming a tent or canopy for camping purposes.

It is the object of this invention to provide a frame for supporting a covering of canvas or similar material which is adapted to be 15 "knocked-down" and packed into a compact bundle suitable for carrying, and which when erected will be so tied and braced as to require no stakes or guys.

Another object is to provide a frame of 20 the above character which may be easily and quickly set up and taken down.

Another object is to provide an interconnection between an upright corner post, a horizontal plate, and an end member where- 25 by the post and plate are hinged together and the end member interlocked therewith, which is especially applicable for use as a tent frame for tents either of the gable or "lean-to" types.

30 With the foregoing objects in view together with such other objects as may subsequently appear the invention consists in the parts and combination, arrangement and construction of parts as hereinafter more 35 fully described and claimed and illustrated in the accompanying drawings in which—

Fig. 1 is a perspective view of the tent frame, as adapted for forming a gable tent, showing it as set up in readiness to receive 40 a covering.

Fig. 2 is a detail in elevation of the peak portion of the gable end member as seen in the direction indicated by the arrow 2 in Fig. 1.

45 Fig. 3 is a plan view of the peak portion of the gable member;

Fig. 4 is a detail in perspective of the end portion of the ridge pole;

50 Fig. 5 is a detail in side elevation showing the manner of assembling the corner post, horizontal plate, end member, and the ridge pole;

Fig. 6 is a view showing the assemblage in end elevation;

Fig. 7 is a detail in construction showing the manner of connecting the corner post to the plate and to the end member; 55

Fig. 8 is a similar view showing the parts as disassembled;

Fig. 9 is a view showing the manner of 60 folding the gable member;

Fig. 10 is a view showing the manner of folding the corner post and plate member;

Fig. 11 is a detail in section as seen on 65 line 11 of Fig. 6;

Fig. 12 is a perspective view showing the frame as adapted to form a tent of the "lean-to" type.

More specifically 11 indicates the plate members, two of which are provided, and 70 hinged on the outer ends of each plate member is a corner post 12. The hinged connection between the post and plate embodies a leaf 13 secured to the post and a leaf 14 fastened on the under side of the plate, the 75 leaves being formed with lugs pivotally connected together by a pivot pin 15 as is common in hinge construction. The leaf 14 is formed with an extension 16, which is offset into the under side of the plate 11 and is 80 downturned at its outer end to form a flange 17, the outer face of which flange extends approximately flush with the end of the plate. The flange forms a channel 18 transversely of the under side of the plate for the 85 purpose hereinafter specified. The post is hinged connected to the plate to swing longitudinally of the latter and to extend substantially parallel therewith when folded, as shown in Fig. 10; the hinge connection 90 being set back from the end of the plate so that when the post is swung to extend at right angles to the plate the extension 16 will project over and seat on the upper end of the post. 95

A pair of gables 19 are provided, each of which consists of two gable members 20—21 connected together by a hinge 22 arranged on the under side of the gable members so that the latter may be folded to extend along side each other as shown in Fig. 9 or to be extended at a suitable angle to 100 form a gable.

Mounted on the outer end of each of the gable members 20—21 is a plate 23 having 105 an end projection 24 adapted to be engaged in the channel 18 and formed on the under side of the plate 23 is a downwardly project-

ing pin 25 adapted to project into a socket 26 formed in a bracket 27 carried on the inner periphery of the corner post 12 to form a tie whereby the upper portions of the corner posts connecting with a gable will be held against spreading.

A ridge pole 28 is provided each end of which is fitted with a hook 29 adapted to be connected to a plate 30 mounted on the 10 inner face of the gable end member, the plate 30 being carried on one gable end member and having an extended bracket portion bent outwardly and inwardly to form a channel 31 on the inner face of the gable near 15 the peak thereof when the gable members are in their open position as shown in Fig. 3.

As a means for bracing the gable end members a pair of brace rods 32—33 are 20 provided which rods are pivotally connected to the gable end members and are connected together by a rule joint 34; the brace rods being adapted to extend in alignment as 25 shown in Figs. 1 and 6 when the gable members are spread and may be folded as shown in Fig. 9.

A brace rod 35 is pivoted on the corner post 12 and has its outer end bent at a right angle to form a hook 36 adapted to be engaged with an eye 37 on the gable end member; this rod serving to brace the corners of the structure laterally.

As a means for holding the brace rod against disengagement from the eye, a guard 35 plate 38 is pivoted on the side of the gable end member; and adapted to be positioned to extend over the rod where the latter is hooked into the eye 37 to prevent the hook 36 from being accidentally disengaged from the eye.

A pair of brace rods 39 and 40 are pivoted on the plate and post as shown in Fig. 5 and are connected together by a rule joint 41; the brace rods 39 and 40 being adapted 45 to extend in alignment to brace the structure longitudinally and adapted to be folded, as shown in Fig. 10.

In assembling the frame the gable members are spread and the ridge pole set in place to connect the gables. The posts are then disposed in a nearly open position as shown in Fig. 8, and the projections 24 on the ends of the gable members are inserted in the channels 18, whereupon the posts are 55 swung to their full open position so that the projection 24 will seat on the upper end of the post with the pin 25 engaging the socket 26 on the bracket 27, thus interlocking the ends of the gable member with the post and plate. On connecting the brace rod 35 to the gable member and opening the brace rods 39—40 the structure will be substantially tied and supported. A cover of canvas or other suitable material may then be placed 60 over the frame thus forming a tent of the 65

square type. The structure thus formed being rigidly braced the use of guy wires or ropes and stakes is unnecessary.

When the frame is knocked down the gable members may be folded together as 70 shown in Fig. 9 and the corner posts and plates folded together as shown in Fig. 10 and with the ridge pole may be tied together in any suitable manner, being preferably wrapped in the canvas covering, thus forming a substantially cylindrical bundle which may be readily transported. Where the frame is adapted to be used in forming a tent of the "lean-to" variety, the gable members are dispensed with and straight end 75 members 42 are employed, the ends of which are provided with the projections 24 and the pins 25 in the same manner as explained in reference to the gable members. The plates in this instance would be formed so 80 as to extend at an inclination relative to the posts, which when the covering is put in place will provide a sloping roof.

While I have shown and described a specific embodiment of my invention I do 90 not limit myself to the exact details of construction shown but may employ such modifications and changes in construction as come within the scope of the appended claims.

I claim:

1. In a foldable tent frame, a plate member, a post hinged to said plate member adapted to be positioned to have its hinged end abut against the under side of the plate member, an end member, a projection on 100 said end member adapted to extend between the end of the post and the plate, and means for effecting a pin and socket connection between said end member and post.

2. In a foldable tent frame, a corner post, 105 a bracket on the inner face of said post, an end member, a projection on said end member adapted to seat on said post, means for detachably connecting the end member to said bracket, a plate member hinged on said post having a projecting end portion adapted when the plate member is extended at right angles to the post to extend over the projection on the end member.

3. In a foldable tent frame, a corner post, 115 a bracket on said post having a socket, an end member, a projection on said end member adapted to seat on said post, a pin on said end member adapted to detachably engage the socket in said bracket, and a plate 120 member hinged on said post having a projecting end portion adapted when the plate member is extended at right angles to the post to extend over the projection on the end member.

4. In a foldable tent frame, a corner post, 125 a bracket on the inner face of said post having a socket, an end member, a projection on said end member adapted to seat on said post, a pin on said end member adapted to 130

- detachably engage the socket in said bracket, and a plate member hinged on said post having a projecting end portion adapted when the plate member is extended at right angles to the post to extend over the projection on the end member, a brace rod connecting the end member to the post, and a brace rod connecting the plate member to the post.
5. In a foldable tent frame, a post, a side plate member, a hinge having one leaf secured to the post and the other leaf attached to the plate member, a projection on the leaf attached to the plate member adapted to extend over the end of the post having a down-
- turned end flange, and an end member having a projection adapted to seat on the end of the post beneath the projection on the leaf and to be engaged by the flange.
6. In a foldable tent frame, a pair of hingedly connected gable members, a plate on one of the gable members having a bracket portion adapted to extend across the joint between said gable members forming a channel, a ridge pole, and a hook on the end of the ridge pole adapted to be engaged with the channel formed by said bracket member.

NICK W. KLINE.
